United States Patent

Des. 239,888
Patented May 18, 1976

239,888

PANTY GIRDLE

Jack J. Lo Cascio, Bayonne, N.J., assignor to International Playtex, Inc., New York, N.Y.

Filed Oct. 3, 1974, Ser. No. 511,872

Term of patent 14 years

Int. Cl. D2—01

U.S. Cl. D2—4

FIG. 1 is a front and top perspective view of a panty girdle showing my new design;

FIG. 2 is a rear and top perspective view; and

FIG. 3 is a right side elevational view, the left side being a mirror image thereof.

I claim:

The ornamental design for a panty girdle, substantially as shown and described.

References Cited

UNITED STATES PATENTS

D. 208,247	8/1967	Bienenfeld	-----	D2—4
D. 229,899	1/1974	Williams	-----	D2—4
3,499,451	3/1970	Strell	-----	128—539

OTHER REFERENCES

Corset & Underwear Review, January 1967, p. 68,
Graceform article No. 326.

Corset & Underwear Review, February 1967, p. 7.

JOEL STEARMAN, Primary Examiner

J. CORRIGAN, Assistant Examiner